ASSIGNORS, BY MESNE ASSIGNMENTS, TO LITHOPRINTEX CORPORATION, A CORPO-
RATION OF DELAWARE

MACHINE FOR TRANSFERRING DESIGNS ON TO CYLINDRICAL SURFACES

Application filed September 20, 1929, Serial No. 393,882, and in Great Britain October 24, 1928.

This invention relates to machines for transferring or offset printing of designs on to cylindrical surfaces, wherein the design on a flat design-bearing surface, is transferred or offset to a resilient curved member, from which it is transferred to a cylindrical surface or roller to be exactly covered by the design. Such a machine is particularly adapted for transferring "ink" from a printing surface to the surface of a roller which by subsequent etching can be transferred into a printing surface to be used for continuous web printing, and the particular type of machine to which the invention relates is that comprising the combination of a flat surface or bed for bearing a design to be transferred, a resilient cylindrical or part cylindrical surface operatively related thereto to receive an impression of the design therefrom, driving means for reciprocating one of said surfaces in relation to the other, a roller for rotatably engaging said cylindrical surface to receive the design therefrom, and means for producing a slight predetermined difference in the peripheral velocities of the roller and its engaging resilient surface, whereby the design as transferred to the roller is lengthened or shortened thereon to cause its ends to meet exactly.

The invention has for one of its objects to provide an improved and simplified construction of machine of the type described above which shall be more accurate and more convenient to operate than those known heretofore. In such machines trip mechanism is provided for ensuring that the cylindrical surface shall be rotated in only one direction by the reciprocation of the bed provided with the flat design-bearing surface, and another object of the invention is to provide an improved construction of such trip mechanism. A further object is to enable the pressure of the roller on the cylindrical surface to be conveniently regulated, and to ensure that the roller shall press uniformly along its length against that surface. A still further object is to mount the platform of the flat design-bearing surface in an improved manner in the machine.

According to an important feature of the

invention, there is provided a machine of the type described wherein the driving means is in the form of a reversible electric motor, and a reversing switch for reversing the direction of rotation of the motor is arranged to be automatically actuated (e. g. by one of the driven surfaces) at the end of the travel of the flat design-bearing surface, in order to effect simplification of, and increased accuracy of working of the machine, and to enable the total height of the machine to be reduced as compared with constructions known heretofore.

According to another important feature of the invention, there is provided a machine of the type described comprising a mutilated gear-wheel serving for driving said cylindrical surface and arranged to be driven by a toothed rack movable to and fro with the bed of said flat design-bearing surface, and locking means arranged to lock said gear-wheel against rotation during the return movement of the rack, in combination with trip mechanism movable with the design-bearing bed and arranged (a) to disengage said locking means at the end of the return movement of the bed, (b) to bring the gear-wheel into mesh with the rack at or near the commencement of the operative stroke of the bed, and (c) to engage the locking means at the end of the operative stroke of the bed. Such trip mechanism occupies only a very small space, comprises parts that are light in weight and is considerably simpler than trip mechanism used heretofore for the same purpose in such machines.

Conveniently, the locking means aforesaid comprises a stop (e. g. a tooth) carried by said gear wheel, a spring-controlled detent movable into and out of locking engagement with said stop, and a catch for holding said detent in its unlocking position, and said tripping mechanism comprises two trip members, one at or towards each end of the design-bearing bed, arranged respectively to coact one with said catch, and the other with said detent at the two ends of travel of the bed.

According to yet another important feature of the invention, there is provided in

a machine of the type described a pivoted lever whereon the roller is journalled, and actuating means (e. g. a rotatable cam) arranged to rock the lever to move the roller into and out of contact with the cylindrical design-transferring surface, in combination with a spring (e. g. a stiff spring) so associated with said lever (e. g. at a situation between its ends) that the spring transmits the force of the actuating means tending to press the roller into contact with the said cylindrical design-transferring surface in order to obviate excess pressure between the roller and the blanket of the cylinder co-acting therewith.

Preferably, the lever aforesaid in which the roller is journalled comprises two separate lever-arms operatively connected together by said spring.

Conveniently, this spring tends to move the lever-arms angularly relatively to one another, and means is provided for limiting such angular movement.

According to another feature of the invention, the lever aforesaid is combined with indicating means associated with said spring for indicating the pressure of the roller on its co-operating cylindrical surface.

Other features of the invention relating to the said trip mechanism, the mounting of the said roller, the track for the bed of the design-bearing surface, and the angular adjustment of the bed will be described hereinafter and pointed out in the claims.

One embodiment of the invention is diagrammatically illustrated, by way of example, in the accompanying drawings, wherein:

Figure 1 is a side elevation showing one form of machine according to the invention, viewed from the side thereof at which the motor is situated,

Figure 2 is a rear end elevation as viewed from the right hand of Figure 1, and

Figure 3 is a top plan view thereof, with certain parts removed, and

Figure 4 is a cross-section taken on the line 4-4 in Figure 3;

Figure 5 is a side elevation of part of the machine shown at the right of Figure 2, illustrating cam mechanism, and the mounting of the roller, and

Figure 6 is a detail perspective view of the cam shown in Figure 5, some parts being shown broken away;

Figures 7, 8 and 9 are detail side elevations of parts of the machine shown at the right of Figure 2, illustrating the mutilated gear wheel and trip mechanism, and

Figure 10 is an end elevation partly in vertical cross-section taken on the bent line 10-10 in Figure 7, Figures 5 to 10 being on a scale larger than that of Figures 1 to 4;

Figure 11 is a side elevation on a still

larger scale showing part of a bearing bracket and its associated pressure-indicating mechanism situated at the left of Figure 2 and carrying the mandrel of the roller, and

Figure 12 is a sectional elevation showing the mounting of the bearing bracket illustrated in Figure 11 and its companion bracket,

Figures 13 and 14 are enlarged detail sections taken on the lines 13-13 and 14-14 respectively in Figure 2 showing parts of rocking mechanism illustrated in Figure 2;

Figure 15 is a vertical section through the platform or carriage taken on the line 15-15 in Figure 3, and

Figure 16 is a wiring diagram showing one form of the electrical connections of the motor and switches controlling the latter.

Like reference characters designate like parts throughout the several views.

Referring to Figures 1 to 4, a main rectangular frame 10 comprises two side-pieces 11, 12 and transverse members 13 connecting the latter together at their lower portions so as to leave the upper part free for a reciprocating platform or carriage 14 for a flat design-bearing surface. Journalled at or near the middle of the two side-pieces is a main shaft 15 that carries at the middle of the frame a driving gear-wheel 16 meshing with a central toothed rack 36 on the underside of the platform 14, and two large diameter rollers 17, 18, one at either side of the wheel 16, the two rollers 17, 18 being identically the same diameter. A worm wheel 19 is keyed on one end of the main shaft 15 outside the side-piece 11 of the frame 10 and meshes with a worm 20 on a shaft 21 that extends lengthwise of the machine and is journalled in bearings on the side-piece 11, a casing 22 being provided for enclosing this worm gearing.

A reversible electric motor 24 of any convenient construction is arranged to drive the worm shaft 21 in any convenient manner, for example as described hereinafter with reference to Figure 16. As illustrated, the motor 24 is mounted on a sill 25 on the side-piece 11 at one end of the shaft 21, to which it is connected by reduction gearing 26, so that the motor drives the main shaft 15 through double reduction gearing. The other end of the shaft 21 is detachably coupled at 27 to one end of a manually-operable shaft 28 that is journalled at 29 in the side-piece 11 and has its free end 30 squared to receive a handle, so that when the motor is not in operation the main shaft 15 can be rotated by hand for idling the platform or carriage 14 to any desired position along the machine.

A track for the platform 14 is in the form of a double line of rollers arranged in pairs, whereof a large diameter pair 17, 18 is at

the middle of the line, the remaining rollers 31, 32 being of small diameter. These smaller rollers 31, 32 are situated at either side of the larger pair towards the ends of the line 5 and are mounted on axles 33 journalled in the side-pieces of the main frame, two rollers on each axle. The bearings of these axles 33 are preferably adjustable in height in the machine in order to take up any wear of the 10 rollers that may occur. The platform 14 carries on its underside two guideways 34, 35 or tracks of inverted L-section, one for each line of rollers, between which is situated the inverted toothed rack 36 meshing 15 with the main spur gear-wheel 16. The platform 14 is thus mounted to run on rollers arranged in a line in the direction of its travel, the axes of rotation of which rollers remain stationary with relation to the frame 20 of the machine during the travel of the platform. The purpose of this arrangement is to reduce the wear as compared with a construction wherein the platform runs on a multiplicity of small free rollers.

25 Any convenient reversing mechanism, comprising for example limit switches 37 and 38, described hereinafter, at or towards the ends of the main frame 10 may be provided for reversing the motor at the end of the 30 forward or operative travel of the platform, and stopping it when the platform returns to its normal or rest position at the front end of the machine as shown in Figures 1 and 3. As compared with the known construction referred to above, wherein a gear wheel driven by a crankshaft rolls between two toothed racks, one fixed at the bottom of the main frame, and the other carried by the platform of the flat design-bearing surface, the described electric drive has the advantage that backlash in the known gearing is obviated, and the total height of the machine can be reduced.

35 As clearly shown in Figures 3 and 4, a bed plate 40 is mounted so as to be adjustable in height on the platform 14 by means of four vertical screw-threaded lifting spindles 41 having squared upper ends. This bed plate 40 carries a design-carrying table 42 which 40 is centrally pivoted in known manner on the bed plate by means of a pivot-pin 43. The upper face of the table 42 is smooth and, when the machine is in use, has a suitable metallic sheet 44 (Figure 15), for example a 45 zinc plate, carrying the design to be transferred stretched over its smooth top which constitutes a bed for the sheet, holes 143 being formed in the table top to afford access to the spindles 41. Any convenient means 50 may be used for stretching the sheet on the table, but preferably so-called 30° parallel-motion grippers 45 known in themselves are used, as illustrated in Figures 3 and 15. Four such grippers 45 are shown at the front edge 55 of the table 42, whilst the rear edge of the

sheet 44 is held by a channel bar 46 bolted along the rear edge of the table. Means for turning the table about its pivot 43 will be described hereinafter.

Extending vertically in known manner 70 from the middle portion of each side-piece of the main frame are pedestals or pillow blocks 51 and 52, as shown in Figures 1, 2, 5 and 7. In these pillow blocks is journalled a shaft 53 carrying, as usual, a cylindrical frame 54 having a smooth periphery. A rubber blanket 55 providing, as usual, the resilient cylindrical surface aforesaid extends any convenient distance round the cylindrical frame 54 and can be stretched over it by any convenient or known means.

75 The larger pair of rollers 17, 18 is preferably situated substantially vertically below the axis of rotation of the cylindrical surface 55, for supporting the travelling bed directly 80 beneath the centre of pressure of the cylindrical surface thereon, and, as illustrated, the shaft 15 is vertically below the shaft 53.

85 The upper ends of the pedestals 51, 52 are extended in the form of, or are otherwise provided with, horizontal arms 56, 57 respectively, in the outer ends of which is journalled a rock shaft 58 (Figures 1, 2, 5 and 12) that lies parallel with the shaft 53 of the cylinder 54. This rock shaft 58 carries 90 a roller, designated generally 59, by means of levers in the form of bearing brackets 60, 61, one on each end of the shaft, as described hereinafter. This roller 59 comprises a mandrel or shaft 62 journalled in the brackets, on 95 which mandrel is secured a cylinder or sleeve 63, for example of copper or brass, for receiving the design.

100 As shown in Figures 5 and 6, a cam 64 is keyed on one end of a short axle 65 journalled in a pedestal 66 on the top of the pillow block 52. A spur gear wheel 67 is keyed on the other end of the same axle 65 and meshes with a mutilated 105 spur gear wheel 68 keyed on the shaft 53 of the blanket cylinder 54. This mutilated gear wheel 68 is arranged to mesh with a toothed rack 69 bolted to the platform 14.

110 A pinion 70 is keyed on the mandrel 62 near its end remote from the cam 64 and 115 meshes with an idler 71 loosely mounted on the shaft 53 at the opposite end from the mutilated gear wheel 68. This idler meshes with teeth 72 on the upper edge of a rack bar 73 which, for the purpose described herein- 120 after, is mounted to move endwise on the platform in any convenient manner, the pitch of the teeth of the toothed rack 73 being less than that of the rack 69.

125 In order that the blanket cylinder may rotate always in one direction and yet be driven by the reciprocating platform 14, the toothed rack 69 is arranged to drive the mutilated gear wheel 68 in only one direction, the arrangement being such that when the plat- 130

form 14 moves from the front to the rear end of the machine in its operative, i. e. design-transferring, direction, indicated by the arrows 99 at the ends of Figures 1, 3 and 8, the mutilated gear wheel 68 is in mesh with its rack 69, and the blanket is rotated into engagement with the design sheet as it passes beneath the cylinder, at a peripheral velocity equal to the velocity of the design sheet, whilst when the platform 14 is returning to its front or loading position in the opposite direction the gear wheel 68 is not rotated.

The gear wheel 68 is wider than the rack 69 and is mutilated (see Figures 7 and 10) by having only a portion 74 of its teeth removed along a chord of the wheel at a situation which is opposite to the toothed rack 69 at the ends of the travel of the platform 14. The pinion 67 is substantially as wide as the gear wheel 68, so that the cam 64 can continue to rotate when the mutilated portion of the gear wheel 68 is adjacent to the pinion 67; the angular velocity of the cam 64 relative to the blanket cylinder is fixed, and is preferably half that of the blanket cylinder. Mounted on the side of the gear wheel 68 at its mutilated portion 74 is a plate 75 having at its side a tooth 77 in line with a mutilated tooth of the wheel and constituting a stop. At the end of the operative stroke of the platform 14 this stop 77 is held by locking mechanism described hereinafter until the platform has moved to the other end of its travel, during which return movement the rack 69 moves idly under the mutilated gear wheel 68 and the roller 63 remains stationary.

As shown in Figures 2, 7, 8 and 9, this locking mechanism comprises a spring-controlled detent 80 pivoted at 81 on the side-piece 12 of the frame 10 and arranged to engage, in its locking position, with said stop 77 which enters into a notch 82 in the detent. A spring-loaded catch 83 pivoted at 84, on the side-piece 12 of the frame 10 is arranged to engage the detent 80 in its unlocking position and hold it therein against the action of its spring 85. Tripping mechanism for controlling said detent 80 comprises two trip members 87, 88 at opposite ends of the rack 69; the member 87 is in the form of a spring-controlled lever that is pivoted at 89 on the side of the platform and is arranged to engage said gear wheel stop 77, when the detent 80 has been disengaged therefrom, at the end of the return stroke of the bed, and to drive the mutilated gear wheel 68 during the first part of the working stroke of the bed and thereby bring the gear wheel 68 into mesh with the rack 69. The second trip member 88 is operative at the end of the working stroke of the design-bearing bed and is also mounted on the side of the platform and has two operative faces 90, 91; the face 90 is arranged to coat with said catch 83 and release it from the detent 80, and the second face 91 is ar-

ranged simultaneously to coat with said stop 77 and position it ready for its engagement by the released detent 80.

The trip member 87 is shown as a double-ended lever, whereof one end is controlled by a spring 92 which tends to rock the second end upwards. The latter end has its lower portion shaped as a cam 93 arranged to engage a transverse stud 94 on the detent 80 and thereby release the latter from the gear-wheel stop 77, whilst its upper portion has in it a notch 95 into which the said stop 77 can snap when the platform has arrived at the end of its inoperative or return stroke. The second trip member 88, shown as a plate, has its two operative faces 90, 91 formed respectively at its lower and upper edges, the lower face 90 being situated somewhat nearer the detent 80 than is the upper face 91 to allow for the distance through which the platform moves during the release of the detent 80 from the stop 77.

When the platform 14 with the rack 69 has completed its operative stroke and is at the rear end of the machine, (i. e. at the right-hand end of Figures 1 and 3 and to the left of Figure 7) and the detent 80 is in engagement with the gear-wheel stop 77, the limit switch 37 is actuated and the movement of the platform is reversed; during the return movement of the platform the shaft 53 and the blanket cylinder 54 remain stationary and the tripping mechanism will occupy the position shown in Figure 7. Near the end of the return stroke the cam 93 on the lever 87 engages a transverse stud 94 on the detent 80, and depresses the latter which is then held in its lower disengaged position by its catch 83. At this moment the lever 87 snaps into engagement with the gear-wheel stop 77, the platform having then arrived at the limit of its travel in the direction of its inoperative stroke (i. e. at the front end of the machine) and has operated the limit switch 38, thereby stopping the motor, as described hereinafter. When the motor 24 is started again its direction of rotation is reversed and, when the operative stroke of the platform begins, the lever 87 in engagement with the gear-wheel stop 77 rotates the blanket cylinder in a clockwise direction, as viewed in Figure 7. This continues until the unmutilated teeth of the mutilated gear wheel 68 mesh with the teeth of the rack 69 for driving it, which rack remains in mesh with the gear wheel 68 until the curved face 90 of the plate 88 contacts with a transverse pin 97 on the catch 83 near its upper end and at the same time locates the gear-wheel stop 77 by means of the face 91 in such a position that the released detent 80 will engage the stop 77. When this occurs the platform is at the limit of its travel in the direction of its operative stroke, (i. e. at the rear end of the machine), the reversing switch 37 is operated, the motor 24 is again

reversed, the platform moves under the gear wheel 68 without rotating the latter, and the motor is stopped when the switch 38 is opened by the platform, the described cycle of operations being then repeated. It will thus be seen that the locking detent 80 locks the cylinder gear wheel 68 against rotation during the return movement of the bed, and that the trip members 87, 88 are arranged to disengage 5 said locking detent from the gear wheel 68 at the end of the return movement of the bed, to bring the gear wheel 68 into mesh with the rack 69 at or near the commencement of the operative stroke of the bed, and to engage the 10 locking detent with the gear wheel 68 at the end of the operative stroke of the bed. The tripping members are small and light and are reliable in operation and constitute a material simplification as compared with tripping mechanism used heretofore in machines 15 of the type described.

As compared with machines of the type referred to known heretofore, the roller 59 is mounted in an improved manner which 20 will now be described. Referring to Figures 5, 11 and 12, the rock shaft 58 has two bushes 100, 101 fast thereon, one at each end, which bushes have each a radial abutment 102, 104, respectively, each in the form of a perforated 25 lug. The said bearing brackets 60, 61 in which the roller 59 is journaled are mounted to rotate each on one of these bushes, and have each a lateral abutment 103, 105 each in the form of a lug. These lugs are arranged 30 in pairs 102, 103 and 104, 105, the lugs of each pair being situated side-by-side but spaced apart with a stiff spring 106, 107, respectively, between them. These springs tend to rock the bearing brackets round the 35 bushes in a direction to press the roller 59 against the blanket cylinder 54. Means in the form of nut-equipped bolts 108, 109 extending each through a perforated lug, and surrounded each by one of the springs, is provided 40 for limiting the angular movement of the brackets 60, 61 about the rock shaft. Split journal blocks 110, 111 for the mandrel 62 are adjustable in known manner by means of a screw 161 in the brackets 60, 61, and the roller 59 can be adjusted towards and 45 away from the blanket cylinder 56 by adjusting the journal blocks in the brackets. A lever arm 112 has one end fast on one end of the rock shaft 58 and carries at its other end an anti-friction roller 113 co-acting with 50 said cam 64 (Figures 5 and 6), whereof the peripheral velocity relative to that of the blanket is fixed, and in the present machine their peripheral velocities are the same. 55 This lever arm 112 is shown distinct from the adjacent bush 101, each being keyed separately to the rock shaft 58, but it may be integral therewith if desired. End plates 300 serve to hold the bush 100 and lever 112 on 60 the shaft 58. A rod 114 pivoted to the arm

112, and a compression spring 115 surrounding the rod 114 serve, in known manner, for thrusting the arm 112 upwards and holding the roller 113 against the periphery of the cam 64. This upward movement of the arm 112 is sufficient to raise the copper sleeve 63 out of contact with the rubber blanket 55 when the roller 113 is engaging certain portions of the cam surface; but when the roller is in engagement with elevated portions of the cam surface the arm 112 is forced down into a position to throw the copper sleeve 63 back into engagement with the rubber blanket. This rocking movement of the arm 112, while sufficient to disengage the roller 59 from the blank, is not great enough to disengage the pinion 70 from its driving gear wheel 71.

The cam 64 shown in Figure 6 is of a construction known in itself and comprises three plates, a central fixed plate 117 and two adjustable side plates 118, 119 which are secured to the central plate by bolts 120, 121 which pass through slots in the side plates and are threaded into the fixed plate. Each plate has a portion of its circumference raised a sufficient height so that when the anti-friction roller 113 is in engagement with that portion the copper sleeve 63 of the roller 59 will be forced into engagement with the rubber blanket, and the different plates of the cam may be so adjusted with respect to each other that there will be a continuous raised portion of the periphery of the cam which will be such as to hold the copper cylinder in contact with the blanket until it has made a complete revolution. Moreover, the two side plates 118, 119 may be so adjusted with respect to the centre plate as to lower and permit the lifting of the copper sleeve 63 at any desired point on the rubber blanket.

Any convenient or known means may be provided for rendering the cam 64 and anti-friction roller 113 inoperative to move the copper sleeve 63 into engagement with the rubber blanket at such times as it is desired to adjust other parts of the machine. As illustrated in Figures 2 and 5, the anti-friction roller 113 is carried by an eccentric disc 123 having its pivots journaled in the forked end of the lever arm 112. One of these pivots carries an adjusting arm 124 having a handle member 125, and the other carries a nut 126 (Figure 1) for fixing the eccentric in its position of adjustment in its fork.

It is desirable that the pressure of the roller 59 against the blanket 55 shall not be too heavy nor too light, and accordingly indicating means associated with said springs 106, 107 are provided for indicating such pressure. Preferably such indicating means are provided at each end of the roller 59 and are similar to one another, so that a description of one will suffice for both.

As shown in Figures 11 and 12, a lever 127 pivotally mounted at one end on the lug 103 of the movable bracket 60, has its other end arranged to actuate, by means of an adjustable screw 128, a pressure indicator 129 mounted on the same bracket. A link 130 has one end pivoted to this lever 127 at a point between its fulcrum and the screw 128, and its other end pivoted to the adjacent lug 102 on the bush 100. Consequently, when the spring 106 is compressed, due to the rock shaft 58 being rotated, the pressure gauge 129 will indicate the amount of compression of the blanket by the roller 59 pressed against it. The described indicators are preferably used as follows:—After setting the roller 59 so that it just contacts with the blanket on the impression cylinder, the dials of the two indicators will be set to zero. Pressure acting through the springs 106, 107 will move the levers 127 and be indicated on the dials so that it can be readily ascertained whether the pressure of the roller 59 on the blanket is uniform along its length, any necessary adjustment being made by shifting a journal block 110 or 111 in its bracket.

Any convenient means may be provided for producing a slight predetermined difference in peripheral velocities of the roller 59 and its engagement surface of the blanket whereby the design, as transferred to the roller, is lengthened or shortened thereon when necessary to cause its ends to meet exactly. One construction of such means in the form of differential gearing of known design comprises a slide block or roller 132 (Figures 2 and 3) arranged to move backwards and forwards in a slideway 133 and shift a short rack 332 meshing with a gear 334 which is arranged to shift the toothed rack 73 meshing with the idler 71. The slideway 133 is pivoted at its front end on the main frame and can be rocked at its rear end by means of rocking mechanism designated generally 134. In the present construction this rocking mechanism comprises a manually-operable screw-threaded spindle 135 mounted in a block 235 (Figure 14) on the side-piece 11 of the main frame. A plate 336 bolted to the slideway 133 has a circular recess for receiving a ring 338 fast on a spindle 339 on a nut member 136 on the spindle so that by turning a graduated handle member 340 on the spindle 135 the slideway can be moved angularly about its pivot towards and away from the side-member 11. Such angular movement that may be required at any time is only small, and the consequential angular movement of the spindle 135 in relation to the side-piece 11 is provided for by the described swivelling construction. The operation of the gearing controlled by this slideway is the same as in known machines of the type referred to above and therefore need not be described in detail. The present con-

struction avoids backlash which is present when worm gearing is employed for rocking the slideways as in the known construction referred to.

In order to correct relative mis-match of the corresponding points in the ends of the design when transferred from the design sheet to the copper cylinder, the table 42 that carries the flat design-bearing surface is mounted on the platform 14 to swivel in its own plane about a central axis of rotation at 43, and adjusting means are provided for angularly adjusting the table. In the improved construction the adjusting means comprises two oppositely-acting screws 140, 141 (Figures 3 and 4) that are mounted on one side of the platform 14 and bear against the table 42 at opposite sides of the transverse vertical plane containing the pivot 43 and, when operated, tend to rotate the table 85 in opposite directions and normally serve each as a stop to hold the table against rotation by the other. This arrangement avoids the use of worm gearing for adjusting the bed of the sheet and consequently obviates the defects due to backlash in such gearing. Preferably the screws are associated with means, such as graduations on the screw-heads, movable in relation to marks on the platform for indicating the angular position in which the bed is set. By means of these screws and graduated scales associated therewith the bed may be rotated above its pivot, in one direction or the other, the exact amount that the ends of the design are found to be mismatched laterally.

As shown in Figure 1, a structure 350 constituting a platform may be mounted on the frame 10 at its rear end for facilitating an operator having access to the upper parts of the machine.

The electrical equipment of the machine will now be described with reference to the diagram Figure 16 which shows the shunt-wound direct-current motor 24 comprising an armature 150 and field winding 151, two double-pole reversing contactors 152, 153 which may be interlocked, a single-pole starting-resistance contactor 154, a main double-pole circuit-breaker 155 and double-pole fuses 156, the mechanically-operated limit or reversing switch 37 (Figure 9), the mechanically-operated limit or stop switch 38 (Figure 8), and also a "forward" switch 159, "reverse" switch 160 and "stop" switch 161, each 110 operable manually. The switches 37 and 38 are on the machine, while the switches 159, 160 and 161 may be mounted elsewhere, e. g. on a panel on the wall of the machine room.

The "forward" contactor 152 has three 125 movable contact arms 162, 163, 164 which, when its winding 165 is energized, contact respectively with the fixed contact-pieces 166, 167 and three contact-pieces 168, 169, 170.

Similarly, the "reverse" contactor 153 has 130

three movable contact arms 172, 173, 174 which, when its winding 175 is energized, contact respectively with the fixed contact-pieces 176, 177 and three contact-pieces 178, 179 and 180.

When these contactors 152, 153 are de-energized the arms 162, 172 rest each against a contact-piece in the form of a back stop 181, 182 respectively, between which is connected a braking resistance 283 for causing the motor to stop rapidly.

The contactor 154, operated by a winding 183, has one movable contact arm 184 that co-operates with a fixed contact-piece 185 and controls a starting resistance 186.

The stop limit switch 38 may be in the form of a double-break spring-controlled plunger switch and is kept closed by its spring except when the platform 14 is at the forward end of its travel and holds it open. The reversing switch 37, which may be a quick make-and-break single-pole change-over switch, and has a handle 187 (Figure 9) and comprises two pairs of contact-pieces 188, 189 and 190, 191, and a switch blade 192 co-operating therewith.

The manually-operated switches 159, 160, 161 are preferably each of the spring-controlled plunger or push-button type, and may have each two fixed contact-pieces 193, 194 and 195, 196 and 197, 198 respectively, the "forward" and "reverse" switches 159 and 160 being normally open and the "stop" switch 161 normally closed as shown.

The contactors are connected in circuit as follows:—One pole of the main switch 155 (e.g. the + pole) is connected by a lead 200 to the contacts 167, 177, and the other pole is connected by a lead 201 to the contact 185 and to one end of the starting resistance 186, whereof the other end is connected to the arm 184 and to the contacts 166, 176. The arms 163, 172 are connected together and to one brush of the motor, the other brush being connected to the arms 162 and 173. A shunt-field-discharge resistance 203 is connected in parallel with the field-winding 151 across the leads 201, 202. One end of the coil 183 is connected to the contact-piece 176 and its other end is connected to the contacts 170 and 180.

The "forward" switch 159, the "reverse" switch 160 and the "stop" switch 161 are connected in circuit as follows:—Contact 198 is connected to the lead 200, and a wire connects the contacts 197, 196, 194 with the contact 169 of contactor 152. The contact 193 is connected to the contact 168 and to one end of the coil 165, whereof the other end is connected to the contact 188 of the reversing limit switch 37. The two contacts 190, 191 of the latter are connected respectively with the contacts 196 and 195 of the "reverse" switch 160, the two contacts 196, 197 being electrically connected together. The contact 195 of this

switch 160 is connected to the contact 178 and to one end of the coil 175, whereof the other end is connected to the movable arm of the stop limit switch 38, whose fixed contact-piece 204 is connected to the contact 189 which is connected to the contact 185.

Assuming that the platform 14 is in its forward or normal end position of loading and that the switches and contactors are in the position shown in Figure 16, if the "forward" switch 159 is closed by hand to traverse the platform, the coil 165 is energized, the contactor 152 is operated and the motor 24 is connected across the mains. The starting-resistance contactor 154 then operates and cuts the starting resistance 186 out of circuit, so that the motor rotates in the direction to impart a forward drive to the platform 14. When the platform arrives at the rear end of the machine a stop 208 (Figure 9) adjustably mounted on the side of the platform operates the reversing limit switch 37 and throws it over against the action of its controlling spring 209, into the position shown in full lines in Figure 9, in which the blade 192 bridges over the contacts 190, 191. The coil 165 is then de-energized so that the "forward" contactor 152 returns to its normal position as shown in Figure 16. The coil 175 of the "reverse" contactor 153, however, is energized so that this contactor 153 is operated and the motor is reversed and driven in the opposite direction. The reverse drive will continue until the platform arrives in its forward position where an adjustable stop 210 (Figure 8) on the side of the platform will open the stop limit switch 38. The coil 175 is then de-energized and the "reverse" contactor 153 returns to its normal position as shown in Figure 16, in which position the resistance 283 is connected in series with the armature 150 for the purpose of causing it to stop rapidly and prevent overrunning.

When the motor was reversed and the platform commenced to return to its front position the spring 209 of the reversing limit switch 37 returned the latter into its normal position, as shown in Figure 16.

If when the motor is running it is desired to stop the platform 14 at any time, it is only necessary to depress the manual "stop" switch 161. The direction of movement of the platform after this "stop" switch has been released will depend on whether the "forward" switch 159 or the "reverse" switch 160 is operated, and whether coil 165 or 175 is energized.

It will be appreciated that the described machine is one of simplified construction, can be built of relatively low height so that the operator can readily inspect the various surfaces to which the design is applied, is accurate in its operation and is of generally improved construction as compared with

those of the same type referred to proposed heretofore.

Various modifications may be made in the details of construction described above without departing from the invention as defined by the claims.

We claim:

1. An offset printing machine of the character described, comprising in combination a reciprocatory bed having a flat surface for bearing a design to be transferred, a toothed rack movable with and extending in the direction of movement of said bed, a resilient cylindrically curved surface operatively related to said flat surface to receive an impression of the design therefrom, a mated gear wheel arranged to mesh with said rack and drive said curved surface, driving means for reciprocating said bed and said rack, a roller for rotatably engaging said curved surface to receive the design therefrom, means for producing a slight predetermined difference in the peripheral velocities of said roller and its engaging resilient surface, a pivoted lever carrying said roller and arranged to move it into and out of contact with said curved surface, a spring associated with said lever and actuating means arranged to coact with said spring and thereby rock the lever and press the roller into contact with said curved surface.
2. An offset printing machine as set forth in claim 1, wherein the trip member operative at the end of the return stroke of the bed is in the form of a spring-controlled lever that is pivoted on the frame of the bed and is arranged to engage said gear wheel stop, when the detent has been disengaged therefrom, at the end of the return stroke of the bed, and to drive the gear wheel during the first part of the working stroke of the bed and thereby bring the gear wheel into mesh with said rack.
3. An offset printing machine as set forth in claim 1, wherein the trip member operative at the end of the working stroke of the bed has two operative faces, whereof one is arranged to coact with said catch and release it from said detent, and the second face is arranged simultaneously to coact with said stop and position it ready for its engagement by the released detent.
4. In an offset printing machine of the character described, the combination of a reciprocatory bed having a flat surface for

bearing a design to be transferred, a resilient cylindrically curved surface operatively related thereto to receive an impression of the design therefrom, driving means for reciprocating said bed, a roller for rotatably engaging said curved surface to receive the design therefrom, means for producing a slight predetermined difference in the peripheral velocities of said roller and its engaging resilient surface, a pivoted lever carrying said roller and arranged to move it into and out of contact with said curved surface, a spring associated with said lever and actuating means arranged to coact with said spring and thereby rock the lever and press the roller into contact with said curved surface.

5. In an offset printing machine of the character described, the combination of a reciprocatory bed having a flat surface for bearing a design to be transferred, a resilient cylindrically curved surface operatively related thereto to receive an impression of the design therefrom, driving means for reciprocating said bed, a roller for rotatably engaging said curved surface to receive the design therefrom, means for producing a slight predetermined difference in the peripheral velocities of said roller and its engaging resilient surface, a pivoted lever comprising two separate lever arms, a spring operatively connecting said arms, which lever carries said roller and is arranged to move it into and out of contact with said curved surface, and actuating means for rocking said lever.

6. A combination of parts according to claim 5, wherein said spring tends to move said lever arms angularly apart, and means is provided for limiting such angular movement.

7. In an offset printing machine of the character described, the combination of a reciprocatory bed having a flat surface for bearing a design to be transferred, a resilient cylindrically curved surface operatively related thereto to receive an impression of the design therefrom, driving means for reciprocating said bed, a roller for rotatably engaging said curved surface to receive the design therefrom, means for producing a slight predetermined difference in the peripheral velocities of said roller and its engaging resilient surface, a pivoted lever carrying said roller and arranged to move it into and out of contact with said curved surface, a spring associated with said lever and actuating means arranged to coact with said spring and thereby rock the lever and press the roller into contact with said curved surface, and indicating means arranged to indicate the pressure of the roller on said curved surface.

8. In a machine of the character described, a rotary cylindrical design-transferring surface, two brackets mounted to rock about an axis parallel to the axis of rotation of said surface, a roller journaled in said brackets,

a lever arm operatively connected to said brackets, and actuating means arranged to rock said lever arm and thereby rotate said brackets and press the rollers against said surface, in combination with pressure-indicating means at each end of said roller, and means for adjusting the pressure at one end of the roller against said surface independently of the other end.

10 9. In a machine of the character described, a rotary cylindrical design-transferring surface, a rock-shaft journalled parallel with the axis of rotation thereof, two bushes fast on said shaft, one at each end and having each 15 a radial abutment, two bearing brackets rotatable each about a said bush and having each an abutment associated each with a said radial abutment to form a pair thereof lying in a plane transverse to the shaft, two compression springs arranged each between the abutments of a pair, means for limiting the movement apart of the abutments of each pair, a roller journalled in said brackets, and a lever arm fast on said shaft for rocking the latter 25 to move said roller towards and away from the cylindrical design-transferring surface.

10 10. An offset printing machine of the character described, comprising in combination a frame having a track extending along the 30 same, a platform which is movable to and fro along said track and has a toothed rack, a driving shaft whereof the axis of rotation is fixed in relation to said frame, a gear wheel fixed on said driving shaft and meshing 35 with said toothed rack, a flat surface for bearing a design to be transferred, carried by said platform, a resilient cylindrically curved surface operatively related to said flat surface to receive an impression of the 40 design therefrom, driving means comprising a reversible electric motor for reciprocating said platform, a reversing switch for reversing the direction of rotation of the motor arranged to be automatically actuated by the 45 platform at one end of the travel thereof, a roller for rotatably engaging said curved surface to receive the design therefrom, and means for producing a slight predetermined difference in the peripheral velocities of said 50 roller and its engaging resilient surface.

11. An offset printing machine as set forth in claim 10, wherein said track comprises a plurality of rollers arranged in a line, the axes of rotation of which rollers remain stationary with relation to the frame of the machine during the travel of said platform.

12. An offset printing machine as set forth in claim 10, wherein said track comprises a plurality of rollers arranged in a line, the 60 axes of rotation of which rollers remain stationary with relation to the frame of the machine during the travel of said platform, a roller at the middle of said line being of substantially larger diameter than that of 65 the other rollers situated at either side there-

of towards the ends of the line, and being situated substantially vertically below the axis of rotation of said curved surface.

13. An offset printing machine as set forth in claim 10, wherein said track comprises a plurality of pairs of rollers arranged in a line, the axes of rotation of which rollers remain stationary with relation to the frame of the machine during the reciprocation of said platform, a pair of rollers at the middle of said line being fast on said driving shaft, one at each side of the said gear wheel on the latter, and being situated substantially vertically below the axis of rotation of said curved surface.

14. An offset printing machine as set forth in claim 10, wherein said track comprises a plurality of pairs of rollers arranged in a line, the axes of rotation of which rollers remain stationary with relation to the frame of the machine during the reciprocation of said platform, a pair of rollers at the middle of said line being fast on said driving shaft, one at each side of the said gear wheel of the latter, which middle pair of rollers is of larger diameter than the diameter of the other rollers situated at either side thereof towards the ends of the line.

In testimony whereof we have signed our names to this specification.

LESLIE LINZELL.
